UNITED STATES PATENT OFFICE.

HENRY L. SCOTT, OF PROVIDENCE, RHODE ISLAND, ASSIGNOR TO HENRY L. SCOTT & COMPANY, A COPARTNERSHIP COMPRISING HENRY L. SCOTT AND DAVID C. SCOTT, OF PROVIDENCE, RHODE ISLAND.

TESTING-MACHINE.

1,335,402.

Specification of Letters Patent. Patented Mar. 30, 1920.

Application filed June 30, 1919. Serial No. 307,643.

To all whom it may concern:

Be it known that I, HENRY L. SCOTT, a citizen of the United States, and resident of the city of Providence, in the county of Providence and State of Rhode Island, have invented certain new and useful Improvements in Testing-Machines, of which the following is a specification.

This invention relates to testing machines for applying tension to different materials to be tested, and the object of this invention is to provide a mechanism of this character that is positive in its tension-applying movement means also being provided whereby the action of the tensioning mechanism may be automatically reversed at a predetermined point in its stroke.

A further object of the invention is to provide means whereby the tension-operating mechanism may be caused to automatically stop at a predetermined point on its return stroke after having completed an operating stroke.

A still further object of the invention is the provision of means whereby the operating mechanism may be caused to automatically reverse its action at the end of both its operating and return strokes for the purpose of applying a so-called fatigue or endurance test to rubber and the like.

With these and other objects in view, the invention consists of certain novel features of construction, as will be more fully described, and particularly pointed out in the appended claims.

In the accompanying drawings:

Figure 1— is a side elevation partly in section illustrating the operating mechanism and also indicating the same as belted to be driven by an electric motor.

Fig. 2— is a side elevation showing the casing in section and illustrating the general arrangement of the driving and reversing mechanisms.

Fig. 3— is a top view illustrating the spring snap reversing mechanism.

Fig. 4— is a sectional view illustrating the nut and worm gear through which the screw receives its traverse motion.

This invention relates more particularly to the mechanism by which the traverse motion of the tension screw or rod is imparted in both directions, while the driving

mechanism runs continuously in one direction.

55

It is found in practice most convenient to employ an electric motor for driving the mechanism but owing to the fact that it is difficult from a practical standpoint to reverse this small motor I have provided means whereby the operating mechanism itself may be automatically shifted to reverse the travel of the tension screw.

To accomplish this reversing action in a simple and practical way I have provided a casing 10 having base flanges 11 which are adapted to be bolted to the upright 12. In this casing I have mounted the traversing tension rod or screw 13 which is arranged to extend through the casing and through the nut 14, see Fig. 4, mounted within the casing. This nut is adapted to be rotated through the worm gear 15 to impart an end-wise motion to said screw, the latter being held from rotating by the key 15^a in the casing sliding in the keyway 16^a in the screw. This gear 15 is provided with hubs 16 which are mounted between thrust bearings 17 at either end thereof.

In order to transmit motion to this worm gear in opposite directions while the driver is running in the same direction, I have provided a frame having a hub 18 pivotally mounted on the upright shaft 19, which frame is provided with a pair of radiating arms 20 arranged to straddle the tension-screw rod 13. Each of these arms is provided with a pair of depending bearings 21 between which are mounted a worm screw 22 on a short shaft 23, on the inner end of which shaft is secured a bevel pinion gear 24 positioned to engage and be driven by the large bevel gear 25. This large gear is mounted on the upright shaft 19 and is itself driven through the pulley 26, short shaft 27 and driving pinion 28, the pulley 26 receiving its motion from the electric motor 30 through pulley 29 and belt 31.

I have spaced these worm screws 22 sufficiently apart so that when the frame is in the center, or non-operating position, neither of the screws will be in engagement with the worm gear, at which time the mechanism may be run idle without imparting a traverse motion to the tension screw. The two arms 20 on the frame are connected to

gether at their outer ends by a web 32 which web slides in the guide 32^a and is slotted as at 33 to receive the upper end of arm 34 of the shift lever 35. This shift lever is mounted to oscillate on the pin 36 and is provided with a laterally extending arm 37 the end of which engages a notch 38 in the shift bar 39. This shift bar is mounted to slide endwise through the casing 10 and one of its edges is provided with three triangular notches 40, 41 and 42 respectively, which are adapted to be engaged by a spring pressed detent 43 whereby this detent will engage notch 42 to retain the shift bar in up position, notch 41 to retain the bar in neutral position, and notch 40 to retain the bar in down position, the front edge of this bar is also notched at 44 to receive the end of the snap shift arm 45. The upper end of this shift bar 39 is provided with an operating handle 46.

The inner end of this snap shift arm 45 is pivoted at 47 in the frame 48 and its extremity is pivoted at 49 to the short arm 50 which is in turn pivoted at 51 also in the frame 48. A pair of springs 52 are connected at one end to a pin 53 in the shift arm 45 and at their opposite end to a pin 54 in the short arm 50, whereby when this arm 45 is carried in either direction beyond a central line through both of the shift arms, these springs serve to throw the arm 45 with a snap to engage and move the shift bar 39 as presently described.

In order to operate this snap shift arm 45 at the desired time I have mounted contact arms 55 and 56 on opposite ends of the tension screw 13, which arms are adapted to engage the adjustable contacting screws 57 in the shift rod 58 and I have provided a pin 59 in the shift rod 58 to engage a slot 60 in the shift arm 45 so that when the tension screw is moved on its downward stroke to exert a tension on the goods to be tested, the arm 55 is set in such a position that after the screw has traversed the desired distance, this arm 55 will engage the upper adjusting screw 57 on the rod 58 and move the rod downward together with the shift arm 45 until this arm snaps by the center and strikes the lower edge 61 of the shift bar 39, which movement throws the shift bar downward and acting through the shift bell crank lever 35 swings the frame in which the worms are mounted, to move one worm out and the other worm into engagement with the driving worm-gear to reverse the action of the tension screw. This tension screw now moves on its return stroke until the arm 56 engages the adjustable screw 57 at the opposite end of rod 58 to move this rod upward until it causes the shift arm 45 to pass the horizontal position when this arm under action of its springs 52 snaps upward against the edge 65 on the shift bar 39

to move the bar upward. In order to control the extent of this upward or reverse motion, I have inserted a stop pin 62 in this rod which limits the middle notch 41 and so cause the worms to be moved to neutral position and so arrest the movement of the tension screw.

In order to again start the screw-feeding mechanism into action it is only necessary to raise the shift bar 39 by its handle 46 to its up position, which movement causes the bell crank lever 35 to move the left hand worm into engagement with the worm gear and start the tension screw in a downward direction.

When it is desired to cause this mechanism to reverse its action at both ends of its stroke automatically it is only necessary to remove the stop pin 62 from the shift rod 58, which will permit the snap shift arm 45 to throw the shift bar upward its full stroke instead of causing it to stop at the neutral point.

This continuous action of the mechanism, first in one direction and then in the other, is employed when it is desired to apply a so-called fatigue test to rubber or other elastic material so as to determine just how many times the rubber may be stretched before it will break.

When it is desired to apply the so-called "set" test to rubber strips it is only necessary to permit the tension screw to descend until it has exerted the proper tension upon the work when by operating the handle 46 by hand the shift bar 39 may be moved to neutral position, which will stop further motion to the tension screw until set in motion by another manual action of this operating handle.

On the upper end of the tension screw I have shown the clamp head 63 which engages the work 64 the rest of the usual tension indicating mechanism not being shown.

The foregoing description is directed solely toward the construction illustrated, but I desire it to be understood that I reserve the privilege of resorting to all the mechanical changes to which the device is susceptible, the invention being defined and limited only by the terms of the appended claims.

I claim:

1. In a testing machine, a screw through which tension is applied for the test, a driving nut engaging said screw, means including a worm gear, and a pair of worms mounted to alternately engage and rotate said worm and nut in opposite directions to impart both an operating and a return movement to said screw.

2. In a testing machine, a screw through which tension is applied for the test, a driving nut engaging said screw, a worm-gear, a pair of worms, means for moving one worm

of said pair to operate said gear nut and screw in one direction and moving the other worm to operate said gear nut and screw in the opposite direction.

5. 3. In a testing machine, a screw through which tension is applied for the test, a driving nut engaging said screw, a worm gear arranged to drive said nut, a frame, a pair 25 of worms mounted in said frame to engage opposite sides of said gear, and a snap shift mechanism controlled by the movement of said screw for moving the opposite worms alternately into engagement with said gear 30 to move said screw endwise in opposite directions.

4. In a testing machine, a rod through which tension is applied for the test, a driving member acting on said rod, means for operating said member to actuate said rod, and means including a spring actuating snap shift mechanism for automatically reversing the direction of travel of said tension rod after an operating stroke.

5. In a testing machine, a screw through

which tension is applied for the test, a driving nut engaging said screw, a worm gear arranged to drive said nut, a frame, a pair 25 of worms mounted in said frame to engage opposite sides of said gear, and a snap shift mechanism controlled by the movement of said screw for moving the opposite worms alternately into engagement with said gear 30 to move said screw endwise in opposite directions.

6. In a testing machine, a screw through which tension is applied for the test, a driving nut engaging said screw, means including a worm gear, a pair of worms mounted to alternately engage said worm on opposite sides to rotate said nut in opposite directions, and means whereby said worms may be shifted automatically at opposite ends of 40 the stroke of said screw to reverse the travel of said screw.

In testimony whereof I affix my signature.
HENRY L. SCOTT.
